UNITED STATES PATENT OFFICE.

WILLIAM R. FOX, OF JACKSON, MICHIGAN, ASSIGNOR TO FOX MACHINE COMPANY, OF JACKSON, MICHIGAN, A CORPORATION OF MICHIGAN.

MULTIPLE-SPEED DRIVING MECHANISM FOR DRILLING MACHINES.

Application filed April 29, 1922. Serial No. 557,327.

To all whom it may concern:

Be it known that I, WILLIAM R. Fox, a citizen of the United States, and resident of Jackson, in the county of Jackson, in the 5 State of Michigan, have invented certain new and useful Improvements in Multiple-Speed Driving Mechanism for Drilling Machines, of which the following is a specification.

My invention relates to multiple drilling 10 machines and particularly to the change gear multiple speed driving mechanism for the spindles which are connected with the drill-tools. I aim to provide a rugged construction of simple and economical form, and one 15 which will permit the attendant to change the gear drive quickly.

Other objects of the invention will appear from the following description:

In the accompanying drawing—

20 Fig. 1 is a central vertical section through the gear box, with the gearing associated therewith;

Fig. 2 is a plan view of part of the mechanism of Fig. 1;

25 Fig. 3 is a vertical sectional view of a modified construction;

Fig. 4 is a detail, and Fig. 4^a is a plan of same.

Figs. 5 and 6 are views of other forms of 30 the invention.

In these drawings 1 indicates the main drive shaft which is arranged centrally of a casing or gear box A. This shaft carries thereto, a master gear member 2 having a plurality of rings of teeth 2^a and 2^b of different diameters, the gear ring of greater diameter being lowermost and presenting an upper surface or ledge 2^c extending beyond the periphery of the gear ring 2^a. Suitable 40 anti-friction bearings are arranged at 1^a and 1^b for the shaft 1.

At points spaced apart around the master gear spindles 3 are located, these spindles being connected with suitable flexible shafting 45 (not shown) through universal joints so that the tools carried in the lower ends of the flexible shafting, may be driven from the spindles 3 when these are rotated. These spindles 3 are provided with key-ways to receive interchangeable pinions, the high speed pinion 6 being adapted to mesh with the lower gear ring 2^b of larger diameter, and these pinions 6 are each provided with a knob or handle portion 6^a reaching up

from the pinion close to the under side of 55 the cover member 8, which closes the open upper side of the gear box. The low speed pinions 7 are provided with keys adapted to fit the key-ways of the spindles and when one of these low speed pinions is slipped 60 into place from the top of the spindle, after the cover has been removed, its key will fit in the key-way of the spindle and the pinion itself will be stopped in the proper position by resting upon the ledge 2^c of the master 65 gear. This low speed pinion is readily accessible upon removing the cover 8 as it is located high on the spindle end close beneath the cover member, and it will be noticed also that the high speed pinion 6 is 70 readily accessible because its knob portion lies close below the lower face of the cover member.

The high speed pinion rests upon a collar 4 which is pinned to the spindle 3, and this 75 collar serves to hold the spindle in proper position because it rests upon a bearing on the bottom 8^c of the gear casing. Each of these spindles is provided with such a collar for holding it in place. The cover member 8 is readily removable and various means 80 may be provided for attaching this cover member to the gear casing. One of these means is shown as consisting of a nut 10 threaded upon a screw stud 10^a extending 85 up from the gear casing, but instead of this construction, a cap screw 10^b may be employed in connection with a U-shaped washer 10^a. This cover member is provided with 90 bearings for the shaft 1, and also for the upper ends of the spindles 3. When it is lifted from the casing the upper ends of the spindles are exposed so that the pinions may be removed by drawing them upwardly 95 along the spindles, and in placing the pinions they may be simply made to register with the spindles and then dropped into place with their keys engaging the key-ways of the spindles. The cover member 100 may also have dowel pins 9 fitting in pockets in the gear casing.

Instead of providing the removable cover member 8 with bearings for the upper ends of the spindles, I may, as shown in Fig. 3, provide in addition to the lower bearings 8^c 105 in the bottom member of the casing, bearings at 12 formed in an intermediate partition a of the casing. Further, instead of

providing in the cover a bearing such as 1^x in Fig. 1 for the main drive shaft, I may provide a bearing at 12' in the intermediate partition, so that the cover is entirely free from bearings for the spindles and main drive shaft.

The cover member, when lifted up for the removal or re-placing of any of the gears, can be held in its elevated position in any suitable manner.

Any one of the pinions can be removed and its spindle then will be idle.

In driving means of the general type described, it is desirable to have the small pinion as small as possible in order to secure high speed of the spindle and at the same time it is desirable to have a rugged construction. Therefore, in making the connection between the small pinion and its shaft, I avoid making a key-way through the pinion back of the teeth, as this would materially weaken the pinion structure, but instead I form the key-way in the upper extension of the pinion which furnishes the handle or knob. The key is shown at 14. This is provided with an end extending at right angles to the main part of the key and riveted into body of the knob or handle.

Referring to Fig. 5 this shows a main cover 8^a dowelled to the main casing at 15, and provided with a plurality of openings 16, one for each spindle, through which the pinions may be lifted out individually and others inserted, without disturbing the main cover 8^a. This construction will permit access to the pinions individually, instead of collectively, as in the first form, and any pinion can be changed for another one without removing the main cover. Each of these openings may have its own cover as shown at 17 and these may simply rest in place or may be attached in any suitable manner.

As shown at 6' the knob of this modification may be provided in the form of a plug held by a pin 18 in the upper flanged part 19 of the pinion, so that when the pinion is in place the plug 6' will rest upon the upper end of the spindle and thus support the pinion on the spindle alone instead of allowing the pinion, as in the first form, to rest either upon the collar 4 or other bearing, or upon the upper side of the master gear. A knob such as described may be provided for each pinion, large or small.

Referring to Fig. 6, I provide covers 17' for the openings in the main cover through which the pinions may be lifted out individually. This form of cover will have bearings for the upper ends of the spindles. They may be fixed in position in any suitable way. They have sockets 17' by which they may be lifted out and the larger pinions may have sockets at 19 by which they may be lifted out. The smaller pinions may have knobs as shown.

While I have shown a two speed drive it will be understood that this is illustrated by way of an example of my invention as a greater number of speed changes can be obtained without changing the principle upon which my invention is based.

For instance, in a four speed drive the members of the central gear cluster would increase in diameter from top to bottom of the series and the different size pinions for these four speeds would be simply dropped onto the spindles and would be stopped at the proper level in any suitable way. The pinions rest by gravity in position to mesh with the master gear rings and in removing them no fastening devices need be manipulated, but on the contrary, the pinions are simply lifted out of place. While I have shown certain forms of the devices only in one figure of the drawings it will be understood that where these forms are susceptible of use in the other figures, they are to be regarded as shown there. Thus the depressions in the upper surface of the pinions shown in Fig. 6 may be used in the pinion 7 of Fig. 1, or the partition *a* of Fig. 3 may be used in any of the other forms, or the feature of supporting the pinions on the upper ends of the spindles may be employed in Fig. 1 and Fig. 3.

It will be understood that the description and drawing forming parts of this specification are presented by way of illustration of the underlying features or principles of the invention, and are not to be regarded as restrictive upon the scope thereof, the latter being defined by the accompanying claims.

Only one pinion occupies a spindle at one time. The rings of gear teeth can be located as close together, one under the other, as gear cutting practice will permit, and thus the height and weight of the gear chest is kept down to a minimum and further weight is also kept down because those pinions which are to be idle are removed from the gear chest.

In some previous form of gear chest where the high and low speed pinions are united in one body in pairs and are shifted to position, one pinion section out of mesh and the other companion pinion section in mesh relative to their respective master gear rings, these rings must be separated by a space greater than the depth of a pinion so that when one section of a pinion is in mesh with its corresponding gear ring, the other section of the pinion will be occupying the said space, where it remains idle, and this space must be of sufficient depth to accommodate the pinion section.

I claim:

1. In a drilling machine a drill spindle, a main driving shaft, a master gear thereon having multiple rings of gear teeth of different diameters with that of the larger

diameter lowermost, and pinions of different diameters to be slipped vertically onto or off from the spindle at its upper end, the downward movement of the pinions being limited to mesh with their respective master gear ring when dropped freely along said spindle, only one pinion occupying a spindle at the same time.

2. In combination in a multiple drilling machine, a casing, a drive shaft, a master gear having a plurality of rings of gear teeth of different diameter carried by the said shaft, spindles located at different points about the rings of gear teeth, and removable pinions of different diameters which may be dropped freely into place on said spindles from the top of the casing the downward movement of the pinions being limited to mesh with the proper gear rings, only one pinion occupying a spindle at one time, substantially as described.

3. In combination in a multiple drilling machine, a multiple speed driving mechanism for the drill spindles, comprising a casing, a main drive shaft, a master gear thereon having multiple rings of gear teeth of different diameters with the gear ring of larger diameter lowermost, a series of spindles for driving the tools arranged about the master gear and bearing in the casing, and interchangeable pinions of different diameters to be removably mounted upon the spindles, to be slipped on or off therefrom at their upper ends, the said pinions resting in place by gravity and being individually freely removable, the pinion of small diameter being limited when dropped freely along the same, to mesh with the large diameter gear ring, and the pinion of large diameter being limited in its downward movement to mesh with the gear ring of small diameter, only one pinion occupying a spindle at one time, substantially as described.

4. In combination in a multiple drilling machine, a multiple speed driving mechanism for the drill spindles, comprising a casing, a main driving shaft, a master gear thereon having multiple rings of gear teeth of different diameters, a series of spindles disposed at different points around the master gear for driving the tools, said spindles bearing in the casing, low speed pinions to be removably mounted on the spindles and limited in their downward movement when slipped thereon to an upper position in respect thereto to mesh with the gear ring of small diameter, and high speed pinions to be removably mounted on the spindles and limited in their downward movement when slipped thereon to mesh with the gear ring of larger diameter, said high speed pinions having knobs or handle portions reaching upwardly therefrom, whereby the pinions may be lifted off from the tops of

the spindles, only one pinion occupying a spindle at one time, substantially as described.

5. In combination in a multiple drilling machine, a multiple speed driving mechanism for the drill spindles, comprising a casing, a main driving shaft, a master gear thereon having an upper ring of gear teeth, and a lower ring of gear teeth of greater diameter than the upper gear ring, spindles arranged at different points about the master gear, bearings in the casing for said spindles, collars fixed to the spindles for bearing on a part of the fixed casing structure to hold the spindles in proper position, high speed pinions removable and re-placeable in respect to the spindles for slipping them off or onto the upper ends of the spindles, said high speed pinions resting upon the collars and having knobs or handles extending upwardly, and low speed pinions also removable from and re-placeable onto the spindles at the upper ends thereof, substantially as described.

6. In combination, a casing, a central drive shaft, a master gear thereon having rings of teeth of different diameters, a spindle arranged alongside of the master gear, interchangeable high and low speed pinions to be removably carried by the spindle, and adapted to be dropped freely into place thereon, the low speed pinion being limited to a position at the upper end of the spindle, and the high speed pinion having a knob or handle reaching upwardly therefrom, said high speed pinion when slipped onto the spindle being limited in its downward movement to mesh with the large diameter gear only, and said low speed pinion when slipped onto the spindle meshing with the small diameter gear ring, only one pinion occupying the spindle at one time, substantially as described.

7. In multiple speed driving mechanism for the drills of drilling machines the combination of a casing, a master gear having multiple rings of gear teeth of different diameters with the one of largest diameter lowermost, spindles located at different points about the master gear and pinions of different diameters removable and replaceable by slipping them off from or onto the upper portions of said spindles, said pinions being automatically stopped at the proper level to mesh with the proper gear, the high speed pinion being seated lowest and the low speed pinion highest only one of said pinions occupying a spindle at one time, substantially as described.

8. In combination in apparatus of the class described, a master gear having rings of gear teeth of different diameters, spindles disposed at different points about the master gear, pinions removably mounted on the upper ends of the spindles and having

- portions supported on the tops of the spindles to determine the location of the pinions along their spindles, substantially as described.
9. In combination in apparatus of the class described, a master gear having rings of gear teeth of different diameters, spindles disposed at different points about the master gear, pinions removably mounted on the upper ends of the spindles and having portions supported on the tops of the spindles to determine the location of the pinions, along their spindles, some of the pinions having longer supporting portions than the others, substantially as described.
10. In apparatus of the class described, a master gear, spindles located about the same, pinions removably mounted on the spindles and having handle portions reaching up therefrom, a key carried by the handle portion and removably engaging a key way in the spindle, and a supporting portion connected to the handle resting on the upper end of the spindle to determine the level at which the pinion will be held on the spindle, substantially as described.
11. In combination in apparatus of the class described, a master gear, spindles disposed at different points about the same, a casing, said spindles at their upper ends being accessible, pinions removably mounted on the upper ends of the spindles and means for stopping the downward movement of the pinions in relation to the spindles and master gear when they are placed upon the upper ends of the spindles, said pinions being interchangeable and only one occupying a spindle at one time, substantially as described.
12. In combination in apparatus of the class described, a master gear having rings of gear teeth of different diameters, a spindle arranged parallel with the shaft of the master gear, a gear box through the top of which the spindle is accessible, interchangeable pinions to be slipped onto and off from the said spindles at their upper-ends, said pinions being automatically stopped at the proper level to mesh with the appropriate gear ring, substantially as described.
13. In combination in apparatus of the class described, a master gear having rings of gear teeth of different diameters, a spindle arranged parallel with the shaft of the master gear, a gear box through the top of which the spindle is accessible, interchangeable

pinions to be slipped onto and off from the said spindles at their upper ends, said pinions being automatically stopped at the proper level to mesh with the appropriate gear ring, for which purpose the spindle has a bearing for supporting the pinion when dropped thereupon from the upper end of the spindle, substantially as described.

14. In combination in apparatus of the class described, a casing, a main drive shaft, master gearing thereon comprising rings of gear teeth of different diameters, spindles at different points about the master gearing, interchangeable high and low speed pinions to be slipped onto said spindles from their upper ends, and freely removable therefrom, each pinion being automatically stopped at the proper level to mesh with the proper gear ring, when moved down along said spindles, only one pinion, high or low speed, occupying a spindle at one time, the said gear rings being arranged one close under the other and at a less distance apart than the depth of either pinion, substantially as described.

15. In combination in apparatus of the class described, a casing, a drive shaft, master gearing having gear rings of different diameters, a spindle extending vertically and parallel with the drive shaft, individual high and low speed pinions to be slipped down along the spindle and each automatically stopped at the proper level to mesh with the proper gear ring, said pinions being freely removable from the spindles by moving them upwardly therefrom, only one of said pinions occupying the spindle at one time.

16. In combination in apparatus of the class described, a casing, a drive shaft, master gearing having gear rings of different diameters, a spindle extending vertically and parallel with the drive shaft, individual high and low speed pinions to be slipped down along the spindle and each automatically stopped at the proper level to mesh with the proper gear ring, said pinions being freely removable from the spindles by moving them upwardly therefrom, only one of said pinions occupying the spindle at one time, the said master gear rings being arranged closer together than the depth of either pinion, substantially as described.

In testimony whereof, I affix my signature.

WILLIAM R. FOX.
